United States Patent Office

Des. 229,923
Patented Jan. 15, 1974

229,923

WHEELCHAIR OR SIMILAR ARTICLE

Morton I. Thomas, 125 South St., Monroe, N.Y. 10950

Filed May 28, 1971, Ser. No. 148,276

Term of patent 14 years

Int. Cl. D6—02

U.S. Cl. D12—131

FIG. 1

FIG. 2

FIG. 3

FIG. 4

FIG. 1 is a side elevational view of a wheelchair or similar article showing my new design;

FIG. 2 is a front elevational view thereof;

FIG. 3 is a rear elevational view thereof; and
FIG. 4 is a top plan view thereof.

I claim:

The ornamental design for a wheelchair or similar article, substantially as shown.
